UNITED STATES PATENT OFFICE.

FRED J. STULP, OF MUSKEGON, MICHIGAN.

WATER-GAGE VALVE.

SPECIFICATION forming part of Letters Patent No. 469,336, dated February 23, 1892.

Application filed February 13, 1891. Serial No. 381,281. (No model.)

To all whom it may concern:

Be it known that I, FRED J. STULP, a citizen of the United States, residing in Muskegon, in the county of Muskegon, State of Michigan, have invented certain new and useful Improvements in Water-Gage Valves; and I do hereby declare the following to be a full, clear, and an exact specification of my said invention.

10 My invention relates to improvements in valves of water-gages used upon steam-boilers.

My invention consists in the novel features of construction and combination of parts described herein, and pointed out in the claims.

15 In the drawings, Figure 1 is a vertical section of my valve with a broken section of the gage-glass. Fig. 2 is a cross-section on the line *x x*, Fig. 1.

I make both the upper and lower valves 20 alike, and therefore show only the lower valve.

The valve consists of a valve-case A, having a horizontal opening through it and also a vertical opening from the horizontal opening. A main-valve stem B, having the valve 25 *b*, enters the horizontal opening and is provided with a thread *b'*, which has its female counterpart *a* in the valve-case A.

The valve is made steam-tight around the 30 main-valve stem by means of a nut *a'* and a packing, as in water-gage valves heretofore in use, and the valve-stem is turned by means of a hand-wheel attached to it in the usual manner. Upon the horizontally-extended 35 part A' of the valve-case is formed a thread *a''*, which screws into the boiler-plate.

40 Removably secured within the horizontal part A' of the valve-case is a tube C, provided with a vertical wall *c*, having a central opening adapted to form a seat *c'* for the valve *b*. Within this tube are two spiders D D', (shown with three legs,) which are bored centrally and form boxes or guides for the check-valve stem E'. These spiders are preferably made 45 integral with the tube. The check-valve E, formed upon or attached to the outer end of the check-valve stem E', is adapted to seat against the valve-seat *c''*, formed at the inner end of the tube C. A coil-spring F, having one end bearing against the valve box or spider D' and the opposite end bearing against the collar *e*, encircles the check-valve stem.

In forming the seats *c'* and *c''* for the main and check valves on the removable tube C the cost of repairing the gage when the valve-seats have become damaged or worn out has been greatly reduced. Heretofore the seat for the main valve has been formed in the main-casing, and in such construction when the valve-seat is defective or has become 55 damaged or worn out it is necessary to supply a new casing, which obviously is considerably more expensive than replacing one of my tubes. Besides, in manufacturing, the valve-seats are more easily accessible for 60 grinding and also for cleaning.

The water-glass G connects with the vertical opening of the valve-case and is attached to the case in the usual manner. A blow-off cock H of any desired construction is attached 70 to the bottom of the lower valve-case.

The operation of the device is as follows: In the drawings all the parts of my valve are shown open or in their normal position when the water-gage is in ordinary use. The valve-stem B of both valves is withdrawn, and at such times the check-valves E remain away from their seats, as the pressure upon both sides of the valves is substantially the same; but should the glass G break the pressure 75 upon the check-valves from inside the boiler will close the same and prevent the escape of water and steam from the boiler. The springs F will sustain the check-valves away from their seats when the pressure upon both sides 80 of the valves is equalized. When a new glass is put into the gage, the check-valves are opened by means of the main-valve stems B, which are turned in till the check-valves E are forced from their seats. The main-valve 85 stems are then withdrawn, so as to leave the check-valves free to close in case of accident to the gage-glass. When it is desired to blow through the gage, the main-valve stems are turned in far enough to strike the check-valve stems E' and hold the check-valves E 90 from their seats, but not far enough to close the opening through the valve-case. The blow-off cock is then opened. While blowing through the gage the pressure on the 95 check-valves will hold the check-valve stems E' against the inner ends of the main valves B.

Should it be desired to positively close the gage at any time, it may be done by turning

the main-valve stems B until the valves b are held against their seats c.

What I claim as my invention, and desire to secure by Letters Patent, is—

- 5 1. In a water-gage, the valve-case A, having the projecting part A', the main valve b, the removable tube C, adapted to fit within the part A' and constructed with a seat c' at its front end for the valve b, a seat c'' at its rear end for the check-valve E, and spiders or boxes D D', and the said check-valve supported and guided in said spiders, substantially as shown and described.
- 10 2. In a water-gage, the valve-case A, having

the projecting part A', the main valve b, the removable tube C, adapted to fit within the part A' and constructed with a seat c' at its front end for the valve b, a seat c'' at its rear end for the check-valve E, and spiders or boxes D D', and the said check-valve supported and guided in said spiders, substantially as shown and described.

FRED J. STULP.
